UNITED STATES PATENT OFFICE.

GEORGE C. LUDGATE, OF BROOKLYN, NEW YORK.

CONTROLLER ATTACHMENT.

1,083,842.

Specification of Letters Patent.

Patented Jan. 6, 1914.

Application filed June 3, 1913. Serial No. 771,510.

To all whom it may concern:

Be it known that I, GEORGE C. LUDGATE, a citizen of the United States, residing at Brooklyn, in the county of Kings and State 5 of New York, have invented new and useful Improvements in Controller Attachments, of which the following is a specification.

The general object of the invention is to improve the mechanism for controlling the 10 motive fluid and the air brakes of a car in point of requiring the driver to use only one hand in effecting the operations of cutting off the power and applying the brakes; and in reducing the time ordinarily required to 15 effect the cutting off of the motive fluid and an application of the fluid pressure brakes. And to this end the invention resides in arranging relatively near to each other those parts of the motive fluid and fluid pressure 20 brake lines which are ordinarily associated with their respective controlling devices, and providing a movable controlling device including an operating handle which, when moved in one direction from a neutral point, 25 will control the passage of motive fluid to the motor and when moved in another direction from the said neutral point, will control the brake operating fluid.

Other objects will appear and be better 30 understood from that embodiment of my invention of which the following is a specification, reference being had to the accompanying drawings forming part hereof, in which:—

35 Figure 1 is a plan of the invention showing it used in connection with the controller box of an ordinary electric car. Fig. 2 is a detail side elevation partly in vertical cross section. Fig. 3 is a detail inverted plan 40 view on the line 3—3 of Fig. 2.

The part which is operated to admit or 45 cut off the supply of motive fluid from a suitable source to the motor, is indicated generally by *a*. In the embodiment shown this part *a* corresponds to the usual movable element which is operated by the controller handle for closing the electric circuit of the motor of an ordinary electric railway car. The part marked *b* corresponds to the stem 50 of what is known as the engineer's valve in a fluid pressure brake system. As will be observed the parts *a* and *b* are relatively near to each other and in the embodiment shown are arranged over the top *c* of the controller box *d*. This bringing of the part *b* into relatively close relation to the part *a*

is had by extending the fluid pressure line *e* to that side of the car on which the controller box *d* is located and thence upwardly over one side of the controller box and to the 60 position shown.

The controller herein indicated generally by *f* includes a casing *5* and a handle *6* detachably connected to mechanism which operates the element *a* when the handle is 65 turned in one direction from the neutral position indicated by full lines in Fig. 3 and which also operates the part marked *b* when the handle is turned in the opposite direction from the neutral position indicated by full lines in Fig. 3. A simple and efficient structure for effecting these results is shown in Figs. 1 to 3 inclusive, where it will be seen that the parts *a* and *b* extend into the casing *5* and each is provided at its 70 upper end with a horizontally disposed toothed wheel *7*. An interrupted tooth wheel *8* is interposed between the wheels *7*—*7* and is fast upon a stub shaft *9* which extends through the top of the casing and is suitably adapted for detachable connection 75 with the operating handle *6*. Now by virtue of the interruption of the teeth in the wheel *8* and the disposing of the said wheel so that its end teeth will barely be in engagement with the teeth of the wheels *7*—*7* when the operating handle is in the neutral position as shown in Fig. 1, it will be manifest that when the said handle is turned 80 away from the observer and to the left in Fig. 1 from the position shown, the wheel *8* will effect the turning of the wheel *7* of the part *a* but the wheel *7* of the part *b* will remain passive by virtue of the toothless part of the wheel *8* turning in the presence 85 of the teeth of the wheel *7* of the part *b*. Continued turning of the handle in this direction admits the motive fluid to the motor *a*, in volume indicated by the pointer 10 and one of the indicator marks *11* on the top 90 of the casing *5*, as shown by dotted lines in Fig. 1.

Now it will be observed that any desired fractional part of the full amount of motive power may be admitted to the motor with 105 this mechanism without disturbing the neutral position of the fluid pressure brake mechanism and in order to further indicate to the operator when the motor is operating at full speed and at the same time to prevent overthrow of the handle *6* and a consequent operation of the fluid pressure 110

brake system, a stop 12 is provided and as shown in Figs. 2 and 3 is in the form of a stud which projects upwardly from a suitable support and into a curved groove 13 in the lower face of the wheel 8. This groove 13 is of such length as will admit of turning the operating handle 6 in opposite directions through arcs of approximately one hundred and eighty degrees from the neutral point indicated by full lines in Fig. 3. At the ends of such turning movements the end walls of the groove will be brought into contact with the stop 12. Now upon turning the handle 6 toward the observer and to the left in Fig. 1 from the position shown, the wheel 7 of the part *b* will be operated, while owing to the toothless part of the wheel 8 the wheel 7 of the part *a* will remain passive. While the wheel 8 is in engagement with the wheel 7 of the part *b* the said part *b* may be jockeyed in the ordinary fashion to gradually overcome the momentum of the car in making an ordinary stop and this without affecting the part *a*. Now it will be observed that in making an emergency stop and with the motor going at full speed, the handle in moving from the position it occupies when the motor is going at full speed, first passes the neutral point before the air brake mechanism becomes operative so that the operation of first cutting off the motive fluid before applying the brakes is positively assured.

Referring now to Fig. 2 a coil spring 14 is arranged in such relation to the operating mechanism hereinbefore described as to hold the wheel 8 normally in such position as will effect the full opening of the engi-

neer's valve *b*. Thus it will be seen that when the controller 6 is in neutral position 40 as shown in Fig. 1, the spring 14 will be tensioned, whereby, and upon release of the controller 6, the wheel 8 will turn under the action of the spring 14 until such spring is relaxed at which time the engineer's valve 45 will be wide open or in the position it will occupy when an emergency application of the brakes is had.

Now with this construction it is manifest that the operator must, under normal conditions or when the car is running, maintain his hand on the controller 6 since the removal of his hand either through accident or inadvertence will remove the resistance to the action of the spring 14, which, under such condition, will operate automatically as before described.

What is claimed as new is:

In combination with the engineer's valve 60 of a fluid pressure brake system and an element for controlling the admission of motive fluid to a motor; of a toothed wheel connected to the engineer's valve, a second toothed wheel connected to the said element, an interrupted gear wheel interposed between 65 said toothed wheels and adapted when turned in either direction to mesh with the said toothed wheels successively, and an operating handle for turning said interrupted gear wheel.

In testimony whereof I affix my signature in presence of two witnesses.

GEORGE C. LUDGATE.
